GARMENT SHOULDER CONSTRUCTION

Joe Davidson and Abraham Davidson, Brooklyn,
and Rosalind d'Albis, Woodstock, N. Y.

Application August 12, 1946, Serial No. 639,962

9 Claims. (Cl. 2—268)

1

The present invention relates to a garment shoulder construction and it particularly relates to a pad construction useful in ladies' garments.

In connection with shoulder pad constructions as presently used in women's garments, these pads usually are sewn into the shoulder of the garment and must be removed upon cleaning or laundering of the garment and then again sewn into position by the wearer or cleaner. It is infrequent that the pad will be sewn back properly into the garment to give the garment the original drape and hang which was designed into it and frequently improper positioning of the pad causes disfigurement of the garment due to unsightly stitching on the exterior of the garment.

It is among the objects of the present invention to provide an improved shoulder construction particularly for light-weight, unlined ladies' garments, such as blouses, dresses, shirtwaists and the like, which will enable removability of any pad placed therein during cleaning and laundering and which will enable ready replacement thereof without departing from the original drape or design of the garment and without necessity of sewing or stitching.

Another object is to provide an improved pad for the shoulder of ladies' garments, the attachment of which will not disfigure the exterior of the garment and which may be readily removed from the garment before cleaning or laundering and readily replaced thereafter.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

A particular feature of the present invention resides in the provision of a floating pocket or receptacle suspended at spaced points along the seams interiorly of the shoulder of a garment, particularly an unlined lady's garment, such as a blouse, coat or dress. The receptacle is preferably provided with an elongated flap closure across the middle of the pocket and along and across the longest dimensions and it is tailored so as to be slightly less concave than the shoulder of the garment at the position where it is attached to the garment so as to give a desired drape to the garment. A pad may readily be inserted into or removed from the pocket. The flap may also extend across the shortest dimension of the pocket.

2

In the drawings which show several of the embodiments of the invention by way of illustration and not by way of limitation,

Fig. 1 is a top perspective view of the exterior of the shoulder of a woman's garment showing the pad pocket in dotted lines,

Fig. 2 is a transverse sectional view upon the line 2—2 of Fig. 1 upon an enlarged scale as compared to Fig. 1,

Fig. 3 is a transverse sectional view upon the line 3—3 of Fig. 1 upon an enlarged scale as compared to Fig. 1,

Fig. 4 is an interior plan view of the shoulder construction with the shoulder of the garment spread out,

Fig. 5 is a perspective view similar to Fig. 1 of an exterior of the shoulder of a garment showing an alternative shape of pocket in dotted lines,

Fig. 6 is an interior plan view of the construction of Fig. 5, with the shoulder spread out,

Fig. 7 is a transverse sectional view upon the line 7—7 of Fig. 5, upon an enlarged scale as compared to Fig. 5,

Fig. 8 is a perspective view similar to Fig. 1 of an interior of a garment showing another alternative shape of a pocket in dotted lines,

Fig. 9 is an interior plan view of the shoulder construction of Fig. 8 upon an enlarged scale as compared to Fig. 8 with the shoulder spread out,

Fig. 10 is a transverse sectional view upon the line 10—10 of Fig. 8 upon an enlarged scale as compared to Fig. 8.

Figs. 11 to 13 are diagrammatic views illustrating the method of forming the pocket so as to give desired concavity thereto, Fig. 11 being a top plan view with the pattern unfolded, Fig. 12 showing the folded pattern and Fig. 13 being an edge view of the pocket.

In the embodiment of Figs. 1 to 3, a blouse A shown having a floating pocket B adjacent to the end of the shoulder and pad C therein. The blouse has a collar 10, attached to the body 15 at the seam 19, a split front 11 buttoned at 12, and a sleeve 13 having the seam 14. The seam 15 connects the sleeve to the body 9 of the blouse A.

The shoulder 20 has three seams, 16, 17 and 18 at the rear, center and front converging toward the seam 9 of collar 10.

The pocket B as best shown in Fig. 3, is tailored to be less concave than the shoulder so that the shoulder will drape properly and it has a transverse flap closure transversely across the middle of its inside face with an inner flap 21 and the outer flap 22. The pocket B is triangular in shape

and it is suspended or anchored at its three corners 23, 24 and 25 to the seams 16, 18 and 19. The pad C may be fitted into the pocket 13 or removed therefrom by opening the flaps 21 and 22. It is not necessary to detach the pocket B which always stays in place during laundering and cleaning, and the attachment of the pocket does not appear from or disfigure the exterior of the garment.

In the embodiment of Figs. 5 to 7, parts functioning the same as those in Figs. 1 to 3 are indicated by the same numerals and letters primed. The pocket B' extends transversely across the middle of the shoulder 20 and is tacked to the single shoulder seam 17 at two points 26 and 27 leaving the corners 23' and 24' unattached. The flap closure 21' and 22' extends transversely across the shoulder as does the closure in Fig. 4, but in Fig. 6 the closure 21'-22' also extends along the long dimension of the pocket B' and not along the short dimension as in Fig. 3.

In the embodiment of Figs. 8 to 9, similarly functioning parts to those shown in Figs. 8 to 10 are indicated by the same numerals and letters provided with a superior 2. The pocket B² is anchored at four points 28, 29, 30 and 31 and the shape of the pocket is semi-circular with the edge 32 curved to fit the shoulder and sleeve connection seam 15². The pocket B² only extends partway up the shoulder 20² and not all the way as in the embodiment of Figs. 1 to 3. The closure flap 21²-22² is parallel to the main shoulder seam 17² and along a radius of the pocket B².

In Figs. 12 and 13, is indicated diagrammatically how the concavity of the pockets B, B' and B² may be controlled. In Fig. 12 for example in forming pocket B², lower part of the circle is shortened so that when the edge 34 is sewn to the edge 35, the material will be concaved toward the shortened section 36 in the lower side of the fold line 45.

There is thus provided in the garment construction of the present invention a permanent receptacle or pocket for a pad which is designed to give drape and hang to a shoulder of a garment, such as an unlined ladies' garment. The pocket may be rectangular, semi-circular, trapezoidal, triangular and it may be floated by attachment at its corners or at its sides (and preferably at the middles of the sides) to the seams in and around the shoulder. The long dimension of the pocket may be along or transverse to the line of the shoulder and the pocket may extend the full length or only part of the length of the shoulder. The flap closure generally extends across the middle of the pocket, either across the long dimension or the short dimension.

As many changes could be made in the above garment shoulder construction and many apparently widely different embodiments of this invention could be made without departing from the scope of the claims, it is intended that all matter contained in the above description or shown in the accompanying drawings shall be interpreted as illustrative and not in a limiting sense.

What is claimed is:

1. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle

of the pocket and a relatively flat readily removable pad fitted into and substantially completely filling said pocket.

2. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said pocket being triangular in shape and stitched in position at its corners.

3. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said pocket being concaved less than the contour of the shoulder so as to give the desired drape effect.

4. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said shoulder having seams and said pocket being sewn in position solely along said seams.

5. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, the flap opening extending along the line of the shoulder.

6. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, the flap opening extending transversely to the line of the shoulder.

7. In combination with the shoulder of an unlined ladies' garment, a floating shoulder pad comprising a floating pocket permanently attached to the interior of said shoulder, having less concavity than said shoulder, attached solely

where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said pocket being sewn in position at the median points of the sides thereof.

8. In combination with the shoulder of an unlined ladies' garment, a floating shoulder pad comprising a floating pocket permanently attached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said flap opening extending across the short dimension of said pocket. 15

9. In combination with the shoulder of an unlined ladies' garment, a floating shoulder pad comprising a floating pocket permanently at-

tached to the interior of said shoulder, having less concavity than said shoulder, attached solely where its edges cross the normal shoulder seams by the stitching of said seams, and extending across said shoulder, having an overlapped flap opening extending transversely across the middle of the pocket and a relatively flat readily removable pad fitted into and substantially completely filling said pocket, said flap opening extending across the long dimension of said pocket.
